UNITED STATES PATENT OFFICE

140,546

DESIGN FOR A HANDBAG FRAME

Joseph L. Friedman, New York, N. Y.

Application November 29, 1944, Serial No. 116,602

Term of patent 7 years

(Cl. D87—2)

To all whom it may concern:

Be it known that I, Joseph L. Friedman, a citizen of the United States of America, residing in New York city, county of New York, and State of New York, have invented a new, original, and ornamental Design for a Handbag Frame, of which the following is a specification, reference being had to the accompanying drawing, forming part thereof, wherein,

The rear of the handbag frame is substantially the same in appearance as the front, with the exception of the closure member.

I claim:

The ornamental design for a handbag frame, substantially as shown, and described.

JOSEPH L. FRIEDMAN.
